UNITED STATES PATENT OFFICE.

BERNARD PATRICK MULLOY, OF NEW ALBANY, INDIANA.

HOT-WATER BOTTLE.

Application filed November 22, 1922. Serial No. 602,615.

To all whom it may concern:

Be it known that I, BERNARD PATRICK MULLOY, a citizen of the United States, residing at New Albany, in the county of 5 Floyd and State of Indiana, have invented certain new and useful Improvements in Hot-Water Bottles; and I do declare the following to be a full, clear, and exact description of the invention, such as will enable others skilled in the art to which it 10 appertains to make and use the same.

My invention relates to improvements in hot water bottles, and more particularly to those which can be used also as parts of 15 fountain syringes.

The object of the invention is to provide an extremely simple yet efficient device of the purpose set forth, having a novel form of air inlet valve which is confined totally 20 within a recess with which the outer end of the filling plug is provided. When the device is used as a hot water bottle, the valve is tightly closed and being then confined within the recess of the filling plug, it will 25 not project to become entangled with bed clothes or the like and furthermore will not be subjected to damage or accidental release.

With the foregoing in view, the invention resides in the novel subject matter herein- 30 after described and claimed, the description being supplemented by the accompanying drawing.

Figure 1 is a front elevation, parts being broken away and in section.

Fig. 2 is an end elevation.

Fig. 3 is an enlarged vertical section through the filling plug and the air inlet valve.

Fig. 4 is a side elevation of a plug which 40 may be used to close the discharge end of the bottle when it is to be used solely as a hot water bottle and not as a fountain syringe.

Fig. 5 is a perspective view of a wrench which is preferably used for removing and 45 applying the several plugs.

In the drawings above briefly described, the numeral 1 designates a metallic water bottle which is preferably formed of aluminum, one end of said bottle having a filling 50 opening closed by a threaded plug 3 which is formed with a large recess 4 opening through its outer end. This plug is provided with a bail 5 by means of which the bottle may be suspended and, when not in use, this 55 bail may be swung substantially into the recess 4.

The end of the bottle 1 opposite the plug 3, is formed with a neck 6 into which either of a pair of plugs 7 and 8 may be threaded, the plug 7 being of such a form as to entirely close the neck 6, while plug 8 is formed with an outlet nipple 9 for connecting a syringe hose thereto. Suitable gaskets 10 are provided for the three plugs 3, 7 and 8, and in order that these plugs may be tightly 60 threaded in place to compress the gaskets and not permit leakage, I prefer to provide a wrench such as that shown in Fig. 5. This wrench includes a straight shank 11 which may be received in a kerf 12 in the outer end 65 of the plug 7 for turning the latter, said shank being provided with a pair of projecting pins 13 for reception in sockets 14 in the plug 3, and being provided with a hooked end 15 to engage a flat sided head 16 70 at the outer end of the plug 8.

In order to facilitate proper flow of water or other liquid from the bottle 1 through the nipple 9, when the bottle is suspended by means of the bail 5, I provide a novel form 80 of air inlet valve which is confined totally within the recess 4. In the construction shown, the bottom of the recess 4 is formed with a central opening in which is threaded a tube 17 carrying an air inlet tube 18. A cylindrical hollow valve body 19 is threaded 85 on the tube 17 against a gasket 20 which bears upon the bottom of the recess 4, the outer end of this body being provided with air inlet perforations 21 and with a central 90 valve-forming boss 22 which is preferably of the conical form shown. A cap 23 is threaded on the outer end of the body 19 and is provided with a central opening 24 which is closed by the boss 22 when the cap 21 is 95 threaded inwardly. Thus, the passage of air or liquid through the pipe 18 is prevented and when the plug 7 is in place, the device 100 may readily be used as a hot water bottle, without any danger whatever of leakage. When the bottle is to be employed as part of a fountain syringe, the plug 8 is substituted for the plug 7 and after filling the bottle by removing the plug 3, it is suspended by means of the bail 5. Thus, when the cap 105 23 is unthreaded to some extent to expose the openings 24 and 21, air may enter the bottle and consequently the free running of liquid therefrom is permitted.

By employing the construction shown or a 110 substantial equivalent thereof, a very efficient article is provided, particular attention

being directed to the housing of the air inlet valve within the recess 4 of the filling plug 3. By this arrangement, when the device is used as a hot water bottle, the valve does not project to become entangled with bed clothes, apparel or the like, and furthermore, even when the bottle is roughly handled, there is no danger of injuring the air inlet valve or of accidentally opening the same when not desired.

As excellent results have been obtained from the details disclosed, these details are preferably followed. However, within the scope of the invention as claimed, numerous minor changes may be made.

I claim:

1. A device of the class described comprising a container having a liquid outlet, a removable filling plug for said container formed with a recess in its outer end and having a threaded air inlet tube at the bot-

tom of said recess, a hollow valve body threaded on said tube and confined within said recess, said body having a perforated outer end provided with a central valve-forming boss, and a cap within said recess threaded on the outer end of said body and having a central opening controlled by said valve-forming boss.

2. A device of the class described comprising a container having a liquid outlet, a removable filling plug for said container having a recess in its outer end, a valve body projecting centrally into said recess from the bottom of the latter, said body having a port for admitting air to the container, and a valve for said port operatively associated with said valve body and confined within said recess.

In testimony whereof I have hereunto affixed my signature.

BERNARD PATRICK MULLOY.
